ISAAC F. WILLEY, OF PHILADELPHIA, PENNSYLVANIA.

IRONING-MACHINE.

1,391,521.

Specification of Letters Patent. Patented Sept. 20, 1921.

Application filed June 10, 1918. Serial No. 239,126.

To all whom it may concern:

Be it known that I, ISAAC F. WILLEY, a citizen of the United States, residing in the city and county of Philadelphia, State of Pennsylvania, have invented a new and useful Ironing-Machine, of which the following is a specification.

My invention consists of a novel ironing machine which is especially adapted for ironing collars preferably presented laterally to the ironing mechanism and is related generally to the general class of ironing machines disclosed in my Patent #1,256,280, dated February 12, 1918.

The primary object of my invention is to provide novel means for the utilization of the main ironing drum as a drier for the collars after being ironed.

My invention further consists in providing means whereby the ironing and drying of the collars is accomplished in one continuous operation around the periphery of the revolving ironing drum.

A still further object of my invention is to provide a plurality of conveyer aprons cooperating with each other, one of said aprons being opposed to the lower periphery of the ironing drum to support the collars in contact therewith after the collars leave the ironing rolls opposed to the upper periphery of the ironing drum, the other apron coöperating with the first mentioned apron to receive the collars therefrom for delivery between the said aprons to the discharge end of the machine, the aprons at the discharge outlet traveling in different directions to most readily effect the discharge of the collars at the desired point.

Another object of my invention is to provide novel tension devices for the conveyer aprons, the apron opposed to the periphery of the ironing drum being provided with an automatic tension means for yieldingly holding said apron in proper contact with the under surface of the drum, while the apron coöperating with said first mentioned apron is provided with a manually operated tension device, the ironing or drying operations in my novel machine being effected with feed and discharge of the collars from opposite ends of the machine on substantially the same horizontal plane.

For the purpose of illustrating my invention, I have shown in the accompanying drawings one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of an ironing machine embodying my invention, certain of the parts being removed for the sake of clearness of illustration.

Fig. 2 represents a section on line 2—2, Fig. 1.

Fig. 3 represents a diagrammatic view showing the organization and relationship of the principal elements of my invention.

Fig. 4 represents a rear elevation of Fig. 1. Similar numerals of reference indicate corresponding parts in the figures.

Referring to the drawings.

1 designates the housing or framework of an ironing machine embodying my invention and adapted to be actuated by any desired type of driving mechanism, the general organization and operation of the ironing elements and their adjuncts being somewhat analogous to that disclosed in my Patent No. 1,256,280, dated February 12, 1918.

Referring to Fig. 1 of the drawings, 2 designates a motor shaft preferably driven by an electric or other motor (not shown) which shaft carries a pinion 3 meshing with a gear wheel 4 mounted on the shaft 5 journaled in the framework 1. The shaft 5 has mounted thereon the pinion 6 meshing with the gear wheel 7 mounted on the shaft 8 also journaled in the housing 1. 9 designates a sprocket wheel mounted on the shaft 8 and provided with a sprocket chain 10 which passes around a sprocket wheel 11 carried by the first ironing roll 12, which latter is preferably carried by the housing 1.

The ironing roll 12 is preferably in frictional engagement with a feed apron 13 which passes around a front roll 14 mounted at the front of the machine for regulating the tension of the apron 13. 15 designates a

rotatable roll preferably adapted to be vertically adjusted to support the lower portion of the apron 13. 16 designates a belt tightening roll journaled in the brackets 5 carried by the framework, said feed apron also passing over a blade 17 adjustably carried by the housing of the machine.

18 designates a roll, which is located out of vertical alinement with the first or upper 10 ironing roll 12, said roll 18 being supported by the housing of the machine and being manually adjustable with respect to the roll 12. These rolls 12 and 18 are simultaneously actuated through the gear 19 on the shaft of the roll 12 meshing with the gear 20 on the shaft of the roll 18. The forward portion of the machine may be provided with a table (not shown) for supporting the collars preparatory to their being placed 20 upon the feed apron 13.

The shaft 8 has also mounted thereon a gear 21, which meshes with a gear 22 carried by the main drum or cylinder 23, which is mounted on the shaft 24 suitably journaled in the housing or framework 1.

Coöperating with the ironing cylinder 23 are a plurality of small ironing rolls 25, any desired number of which may be employed, the organization and operation of these rolls 30 being in a general way substantially similar to those disclosed in my patent heretofore referred to.

The shafts of these rolls 25 are provided with the pinions 26 in mesh with a gear 27, 35 Fig. 4, on the shaft 24 of the drum 23, so as to drive the rolls 25 in unison with said drum.

28 designates steam conduits by means of which steam is circulated through the large 40 drum or cylinder 23, and 29 designates similar steam conduits, whereby steam is circulated through the first ironing roll 12.

The particularly novel features of my present invention will now be described:

45 Referring more particularly to Fig. 3 of the drawings, 30 and 31 designate a plurality of continuous conveyer aprons adapted to coöperate with each other, one of which 30 coöperates with, by passing beneath, the ironing cylinder or large drum 23, in drying the collars or other articles to be ironed. This apron 30 toward the front of the machine and in proximity with the under surface of the drum 23 passes over and is 55 driven by the roll 32 mounted on the shaft 33 journaled in a bracket on the housing of the machine. This shaft 33, (see left of Fig. 4) has mounted thereon a sprocket wheel 34 provided with a sprocket chain 35 which passes around the sprocket wheel 36 mounted on the shaft 8 to impart motion to the apron 30.

37 and 38 designate idler rolls located in adjacency to the periphery of the ironing 60 drum 23 to hold that portion of the apron 30

which travels beneath the under surface of the drum in contact with it to effect the ironing of the collars. The shaft of the roll 37 is journaled in a bracket on the housing of the machine at the front portion of the 70 drum, while the shaft of the roll 38, located at the rear portion of the drum, is supported in the bearing blocks 39 secured to rectangular frames 40 fastened to the side frames of the machine. 75

41, 42, 43, 44 and 45 designate idler rolls for supporting and guiding the circuitous path of travel of the apron 30. The shafts of the rolls 41 and 42 are journaled in brackets on the housing of the machine, 80 while the shafts of the rolls 42, 44 and 45 are mounted on the bearing blocks 46 secured to the rectangular frames 40. 85

47 designates a gravity tension roll which is carried in a loop 68 of the apron 30, and 90 is yieldingly supported in the rectangular frames 40. The roll 47 is provided with a shaft 70 rotatably journaled in brackets 49, Fig. 2, integral with sleeves 50 vertically movable on vertical posts 51 secured in the rectangular frames. The sleeves 50 are also connected by the shaft 70 rotatably journaled in the brackets 71 of the sleeves 50. The shaft 70 is provided at its ends with pinions 52 meshing with racks 53 on each 95 side of the machine. This tension device serves to take up the slack in the apron 30 and hold the roll 47 at all times in parallelism with the other rolls of the machine.

72 designates a hand wheel secured on the 100 shaft 70 to manually raise or lower the roll 47 to lessen or increase the tension of the apron 30.

The apron 31 toward the front of the machine passes over and is driven by the roll 54 105 mounted on a shaft provided with a gear 55 in mesh with a gear 56 mounted on the driven shaft 8.

The apron 31 moving in the direction of the arrows, from the roll 54, in its passage 110 to the rear of the machine, passes over the roll 32 and is brought into engagement with the apron 30 which also passes over the roll 32 and thence travels in engagement with the apron 30 until the roll 41, beneath which both aprons travel, is reached, when it leaves the apron 30 and is not again brought into contact with said apron 30 until both pass beneath the roll 43, after which both aprons travel together upward to and over the roll 120 44. Thence apron 31 travels downwardly over the idler roll 57 supported in the bracket 58 secured to the housing of the machine, and then passes toward the front of the machine over the idler roll 59, the tension 125 60, the idler rolls 61 and 62 and back to the driven roll 54.

The tension roll 60 for regulating the tension of the apron 31 is adjusted by being supported on the screws 63, mounted on each 130

side frame of the machine and equipped with internally threaded sleeves 64 provided with boxings in which the ends of the shaft of the roll 60 are rotatably journaled, as shown in

5 Fig. 1.

65 designates brackets secured to the rectangular frames 40, on which below the discharge mouth of the aprons 30 and 31 is supported a table or compartment 66 to receive the ironed collars.

10 The operation of my novel embodiment of the conveyer aprons in connection with a collar ironing machine of the class referred to will now be readily apparent to those skilled 15 in this art and is as follows:—

I will first briefly refer to the operation 20 of ironing the collars by the ironing rolls from whence the collars are delivered to the conveyer aprons for further drying and delivery to the discharge table or compartment.

Assuming that the various parts of the machine are in properly adjusted positions, the motor (not shown) is started to revolve 25 the shaft 2. The shaft will then revolve the gear 3 and thereby the gears 4, 6 and 7, which in turn will occasion the revolution of the sprocket wheel 9 and thereby actuate the sprocket chain 10, with the result of imparting rotation to the ironing roll 12. Since the ironing roll 12 is intergeared with the roll 18 and in frictional engagement with the belt 13, which passes between said ironing roll and said roll 18, a forward feeding 30 movement will be imparted to the feed apron 13. The gear 21 which is mounted on the same shaft 8 on which the sprocket wheel 9 is mounted, meshes with the gear 22 and thereby revolves the drum 23. The collars, 35 after being washed and having been treated with starch in any desired manner, are in condition to be ironed.

The operator having arranged the collars to be ironed with their bottoms or inner 40 faces upon and transversely of the apron 13, the collars are then fed laterally by the feed apron to beneath the first ironing roll 12 and in parallelism with its axis with the result that substantially the entire upper 45 surface of each collar will be brought into engagement with the ironing surface of the roll 12 and properly ironed.

After the collar passes beyond the ironing roll 12, it travels on and over the blade 50 55 17 and is delivered to the ironing drum 23 laterally in parallelism with the axis thereof. It then passes beneath the first ironing roll 25, then beneath the second ironing roll 25, then beneath the third ironing roll 25 of the 60 first set of rolls in each instance in parallelism with their axes, and thereafter similarly beneath the remaining rolls.

The collars after being as aforesaid molded and ironed are carried downwardly on 65 the face of the revolving ironing drum 23 to

engage with the apron 30 moving with said drum and adapted to hold the collars in contact with the under surface of the ironing drum to give them a thorough drying.

The delivery of the collar between the 70 ironing drum and the apron 30 is into a pocket 67 formed by slightly spacing the roll 38 from the periphery of the ironing drum.

The drying operation takes place substantially around the under surface of the drum from the roll 38 to a point where the apron 30 is directed forwardly and downwardly over the roll 37 away from the drum 23,— the apron 30 carrying the collars with it, 75 from it to be transferred to the apron 31 and carried between the two aprons on an incline toward the rear of the machine and around the roll 41. Beyond the roll 41 the aprons 80 diverge, the collar being carried on the apron 31 to the roll 43 where the aprons again meet to convey the collar upwardly to between the rolls 44 and 45, the different direction of travel of the two aprons at this 85 point effecting a discharge outlet for the 90 collar into the receiving compartment 66.

The gravity roll 47 carried in the loop 68 of the apron 30, controls the tension of the apron to yieldingly hold the apron 30 with respect to the drum 23, whereby the 95 collars under various conditions are properly conveyed between the drum and the apron.

The tension of the apron 31 is controlled by the tension roll 60 engaging the loop 100 69 of the apron and adapted to be controlled by the manually operated threaded members 63 to hold the apron 31 at the proper tension in respect to the apron 30.

By my invention, I provide means for 105 utilizing for drying purposes a considerable portion of the under surface of the ironing drum, the feed and discharge of the collars being effected from the opposite ends of the machine.

It will now be apparent that I have devised a novel and useful construction of an ironing machine which embodies the features of advantage enumerated as desirable in the statement of the invention and the 110 above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what 115 I claim as new and desire to secure by Letters Patent, is:—

1. An ironing machine, which comprises in combination, a revoluble ironing drum, a plurality of ironing rolls of relatively small 120 125 130

diameter opposed to the periphery of said drum at the upper portion of the machine, said juxtaposed small diameter ironing rolls being collocated in such close relationship to each other and to the upper periphery of said drum as to effect the feeding forwardly and continuous progression of a collar presented laterally to said rolls with its longitudinal axis in substantial parallelism to said rolls, 10 a plurality of upper and lower continuous conveyer aprons which coöperate with each other and one of which is opposed to the periphery of said drum near the lower portion of the machine, means for driving said 15 aprons in unison with said revoluble drum and said ironing rolls, means for the continuous delivery of the ironed collars to the conveyer apron opposed to said ironing drum, means for transferring the collars to and 20 upon the lower coöoperating conveyer apron, means for forming a loop in the upper rear portion of said upper apron, a gravity tension roll supported in said loop, means for adjusting said roll, means for forming a 25 loop in the lower front portion of said lower apron, a lower front tension roll in said latter loop, and means for adjusting the tension of said lower front tension roll.

2. An ironing machine, which comprises 30 in combination, a revoluble ironing drum, a plurality of ironing rolls of relatively small diameter opposed to the periphery of said drum at the upper portion of the machine, said juxtaposed small diameter ironing rolls 35 being collocated in such close relationship to each other and to the upper periphery of said drum as to effect the feeding forwardly and continuous progression of a collar presented laterally to said rolls with its longitudinal 40 axis in substantial parallelism to said rolls, a plurality of upper and lower continuous conveyer aprons which coöperate with each other and one of which is opposed to the periphery of said drum near the lower portion 45 of the machine, means for driving said aprons in unison with said revoluble drum and said ironing rolls, means for the continuous delivery of the ironed collars to the conveyer apron opposed to said ironing drum, 50 means for transferring the collars to and upon the lower coöoperating conveyer apron, means for supporting the collars in travel between said aprons, means for forming a loop in the upper rear portion of said upper 55 apron, a gravity tension roll supported in said loop, means for adjusting said roll, means for forming a loop in the lower front portion of said lower apron, a lower front tension roll in said latter loop, and means for 60 adjusting the tension of said lower front tension roll.

3. An ironing machine, which comprises 65 in combination, a revoluble ironing drum, a plurality of ironing rolls of relatively small diameter opposed to the periphery of said

drum at the upper portion of the machine, said juxtaposed small diameter ironing rolls being collocated in such close relationship to each other and to the upper periphery of said drum as to effect the feeding forwardly and continuous progression of a collar presented laterally to said rolls with its longitudinal axis in substantial parallelism to said rolls, a plurality of upper and lower continuous conveyer aprons which coöperate with each other and one of which is opposed to the periphery of said drum near the lower portion of the machine, means for driving said aprons in unison with said revoluble drum and said ironing rolls, means for the continuous delivery of the ironed collars to the conveyer apron opposed to said ironing drum, means for transferring the collars to and upon the lower coöoperating conveyer apron, means for supporting the collars in travel between said aprons, means for forming a loop in the upper rear portion of said upper apron, a gravity tension roll supported in said loop, means for adjusting said roll, means for forming a loop in the lower front portion of said lower apron, a lower front tension roll in said latter loop, and means for adjusting the tension of said lower front tension roll, means for discharging said collars from said conveyer aprons, in combination with means for initially applying heat and pressure to the upper side and pressure to the under side of the forwardly moving collar throughout the length thereof.

4. An ironing machine, which comprises 100 in combination, a revoluble ironing drum, a plurality of ironing rolls of relatively small diameter opposed to the periphery of said drum at the upper portion of the machine, said juxtaposed small diameter ironing rolls 105 being collocated in such close relationship to each other and to the upper periphery of said drum as to effect the feeding forwardly and continuous progression of a collar presented laterally to said rolls with its longitudinal 110 axis in substantial parallelism to said rolls, a plurality of upper and lower continuous conveyer aprons which coöperate with each other and one of which is opposed to the periphery of said drum near the lower portion 115 of the machine, means for driving said aprons in unison with said revoluble drum and said ironing rolls, means for the continuous delivery of the ironed collars to the conveyer apron opposed to said ironing drum, 120 means for transferring the collars to and upon the lower coöoperating conveyer apron, means for forming a loop in the upper rear portion of said upper apron, a gravity tension roll supported in said loop, means for 125 adjusting said roll, means for forming a loop in the lower front portion of said lower apron, a lower front tension roll in said latter loop, and means for adjusting the tension of said lower front tension roll, means for 130

feeding and discharging said collars from opposite ends of said machine and at substantially the same horizontal plane, in combination with means for initially applying 5 heat and pressure to the upper side and pressure to the under side of the forwardly moving collar throughout the length thereof.

5. An ironing machine, which comprises in combination, a revoluble ironing drum, a 10 plurality of ironing rolls of relatively small diameter opposed to the periphery of said drum at the upper portion of the machine, said juxtaposed small diameter ironing rolls being collocated in such close relationship to 15 each other and to the upper periphery of said drum as to effect the feeding forwardly and continuous progression of a collar presented laterally to said rolls with its longitudinal axis in substantial parallelism to said rolls, 20 a plurality of upper and lower continuous conveyer aprons which coöperate with each other and one of which is opposed to the periphery of said drum near the lower portion of the machine, means for driving said 25 aprons in unison with said revoluble drum and said ironing rolls, means for the continuous delivery of the ironed collars to the conveyer apron opposed to said ironing drum, means for transferring the collars to and 30 upon the lower coöoperating conveyer apron, means for forming a loop in the upper rear portion of said upper apron, automatic means in said loop for yieldingly holding the upper of said aprons against the periphery of 35 the ironing drum, means for forming a loop in the forward portion of said lower apron, a tension roller in said loop, and means for actuating said tension roller.

6. An ironing machine, which comprises 40 in combination, a revoluble ironing drum, a plurality of ironing rolls of relatively small diameter opposed to the periphery of said drum at the upper portion of the machine, said juxtaposed small diameter ironing rolls 45 being collocated in such close relationship to each other and to the upper periphery of said drum as to effect the feeding forwardly and continuous progression of a collar presented laterally to said rolls with its longitudinal 50 axis in substantial parallelism to said rolls, a plurality of upper and lower continuous conveyer aprons which coöperate with each other and one of which is opposed to the periphery of said drum near the lower portion 55 of the machine, means for driving said aprons in unison with said revoluble drum and said ironing rolls, means for the continuous delivery of the ironed collars to the conveyer apron opposed to said ironing drum, 60 means for transferring the collars to and upon the lower coöoperating conveyer apron, means for forming a loop in the upper rear portion of said upper apron, automatic means in said loop for yieldingly holding the 65 upper of said aprons against the periphery

of the ironing drum, and front and rear means manually operated to control the tension of said aprons relative to each other.

7. In an ironing machine, a single revoluble ironing drum, a plurality of upper ironing rolls of relatively small diameter opposed to the upper periphery of said drum in such close relationship as to cause the progression of a collar to be ironed with its longitudinal axis in parallelism to said upper small rolls, a lower conveyer apron 30 located under and in proximity to said drum, a front driving roll 32 for said apron, a front idler roll 37 for said apron located near the front under portion of said drum, a rear upper idler roll 38 for said apron located at the rear of said drum, an idler roll 41 located under said drum under which said apron travels, an intermediate idler 42 on which said apron travels, a rear idler 43 under which the rear lower portion of said apron travels, a pair of upper rear idlers 44 and 45 around which said apron travels, said apron being formed into an upper loop 68 at a point between said upper rear idlers 45 and 38, a gravity tension roll 47 supported on said loop 68, a second apron 31 having portions located in proximity to said apron 30, means for actuating said last mentioned apron, and means in the front of the machine 90 for taking up slack in said latter apron.

8. In an ironing machine, a single revoluble ironing drum, a plurality of small ironing rolls closely arranged in proximity to the top of said drum, a lower conveyer apron 100 located under and in proximity to said drum, a front driving roll 32 for said apron, a front idler roll 37 for said apron located near the front under portion of said drum, a rear upper idler roll 38 for said apron located at the rear of said drum, an idler roll 41 located under said drum, under which said apron travels, an intermediate idler 42 over which said apron travels, a rear idler 43 under which the rear lower portion of said apron travels, a pair of upper rear idlers 44 and 45 around which said apron travels, said apron being formed into an upper loop 68 at a point between said upper rear idlers 45 and 38, a gravity tension roll 47 supported in said loop 68, means for adjusting said tension roll vertically, a second apron 31 having portions located in proximity to said apron 30, a drive roll 54 for said latter apron which passes around said rolls 32, 41, 43 and 44, 110 front idler rolls 62 and 61, and rear idler rolls 59 and 57 for said latter apron, a front tension roll for said latter apron, and means at the front of the machine for adjusting said front tension roll.

9. In an ironing machine, a single revoluble ironing drum, a plurality of small ironing rolls, closely arranged in proximity to each other and to the top of said drum, upper and lower aprons arranged below said drum, 130

means for actuating said aprons, idler rolls for said aprons, means for forming a loop in the upper rear portion of said upper apron, a gravity tension roll supported in said loop, 5 means for adjusting said tension roll, means for forming a loop in the lower front portion of said lower apron, a tension roll in said

loop, and means for adjusting said tension roll.

ISAAC F. WILLEY.
